UNITED STATES PATENT OFFICE.

WILLIAM TURNOR LEWIS, OF RACINE, WISCONSIN, AND MILTON MERWIN EELLS, OF CHICAGO, ILLINOIS, ASSIGNORS TO WESTERN COIL & ELECTRICAL CO., OF RACINE, WISCONSIN.

DESIGN FOR A RADIOCABINET.

Application filed September 20, 1926. Serial No. 19,117. Term of patent 14 years.

To all whom it may concern:

Be it known that we, WILLIAM TURNOR LEWIS and MILTON MERWIN EELLS, respectively, citizens of the United States, residing at Racine and Chicago, in the counties of Racine and Cook, and States of Wisconsin and Illinois, have invented a new, original, and ornamental Design for a Radiocabinet, of which the following is a specification, reference being had to the accompanying drawing, forming part thereof.

The figure is a perspective view of the radio cabinet, showing our new design.

We claim:

The ornamental design for a radiocabinet, as shown:

In testimony that we claim the foregoing we have hereunto set our hands at Racine, in the county of Racine and State of Wisconsin.

WILLIAM TURNOR LEWIS.
MILTON MERWIN EELLS.
